UNITED STATES PATENT OFFICE.

MORRIS SACHS, OF NEW YORK, N. Y.

DESIGN FOR A LEGGIN.

SPECIFICATION forming part of Design No. 22,603, dated July 11, 1893.

Application filed April 27, 1893. Serial No. 472,130. Term of patent 3½ years.

To all whom it may concern:

Be it known that I, MORRIS SACHS, of New York, in the county and State of New York, have invented and produced a new and original Design for a Leggin, of which the following is a specification.

The accompanying drawing is a side elevation of a leggin showing my design.

The leading feature of my design is the representation of an ornamental band extending centrally from top to bottom of the side surface of the leggin.

1 is the side surface of a leggin and 2 represents an ornamental band extending ap-

proximately in a central direction from top 15 to bottom of the side surface 1. The right edge of the band 2 is straight with the exception of the curved or hollow portion 3 at its upper end. The left edge of the band 2, has hollows or curved portions 4 and at intervals V shaped recesses 5 on each of the side edges of the surface, 1, is shown a bead 6. 20

What I claim is—

The design for a leggin as herein set forth.

MORRIS SACHS.
